(57) **CLAIM**

The ornamental design for a gate as shown and described.

DESCRIPTION

FIG. 1 is an isometric top, front, right view of a gate;

FIG. 2 is a front view thereof;

FIG. 3 is a rear view thereof;

FIG. 4 is a left view thereof;

FIG. 5 is a right view thereof;

FIG. 6 is a top view thereof;

FIG. 7 is a bottom view thereof; and,

FIG. 8 is a front perspective view showing the gate in a position of use.

The broken lines in the drawings are included for the purpose of illustrating subject matter that forms no part of the claimed design.
